JOHN C. WORTHINGTON, OF NEW YORK, N. Y.

AMPHIBIAN LANDING GEAR

Application filed October 22, 1938. Serial No. 313,993.

Special objects of the present invention are to provide landing gear for airplanes readily applicable to "land" planes for enabling such planes to alight on water as well as on land.

The invention involves, generally speaking, the provision of floats or pontoons and the attachment and mounting of same, so that they may be raised or lowered over the landing wheels of the plane.

Other novel features of the invention will appear as the specification proceeds.

In the drawing accompanying and forming part of the specification, one practical embodiment of the invention is illustrated, but it should be understood that the structure may be modified as regards this disclosure without departure from the true spirit and broad scope of the invention.

Fig. 1 is a side elevation of an airplane of the land type as equipped with the invention and modified to form an amphibian type of plane; Fig. 2 is a broken front elevation showing the floats as lowered over the landing wheels for alighting on water; Fig. 3 is a similar view showing the floats raised to expose the landing wheels for alighting on land; Figs. 4 and 5 are fragmentary cross-sectional views through one of the floats illustrating the same in the raised and lowered positions; Fig. 6 is a fragmentary sectional view and on substantially the plane of line 6—6 Fig. 5.

The land plane illustrated is shown as equipped, as usual, with the landing wheels 7 and suitable tail skid 8. The wheels are shown carried by posts in which there may be incorporated at 9 the usual shock absorbers. These posts may be suitably braced and connected with the fuselage to carry the landing load.

Movable over and with respect to the landing wheels are the floats 10 connected in parallelism by cross bars 11, spaced fore and aft a proper distance and suitably connected with the floats to hold them firmly in parallel relation.

The floats have wells 12 for the wheels provided by transverse bulkheads 13, Fig. 6, which, as indicated in Figs. 4 and 5 have

openings 14 at the bottom to pass the landing wheels when the floats are raised as in Figs. 3 and 4. These wheel openings are indicated as relatively narrow slots, just wide enough to freely pass the wheels and adapted to be closed by cooperating sliding doors 15, when the float is lowered as in Fig. 5. These doors are indicated as sliding in guides 16 down over the inclined bottom portions of the hull and meeting at the keel line.

Automatic opening and closure of the wheel wells is effected in the illustration by means of bell cranks pivotally supported at 17 on brackets 18 at opposite sides of the wheels having arms 19 engaging the wheel yokes 20 and longer arms 21 having pin and slot connections 22 with the slides. The opening and closing action may be assisted by springs 23 acting on the pivot shafts 17 which carry the bell cranks.

The wheel yokes are indicated in Figs. 4, 5 and 6 as having edge flanges 24 sliding over edge shoulders 25 on the brackets 18, which brackets therefore operate as guides 75 sliding over the wheel structures to guide the floats in their up and down movements and to brace the floats to the landing gear posts.

Suitable means for quickly lowering or raising the floats are provided, such means being here illustrated as reversely threaded screw shafts 26 journalled across the fuselage and carrying nut blocks 27 to which are pivotally connected the links 28 pivoted at their lower ends at 29 to the float gear in line with the cross braces 11. The screw shafts are shown as driven in unison by bevel gearing 30 and upright shafts 31, which latter are turned by spiral gearing 32 from a control shaft 33 operated by suitable motive power, or, for instance, by hand crank 34.

It will be seen that operation of the cross screw shafts by the hand crank mechanism described will effect a drawing together or separation of the nut blocks, and hence a lifting or lowering action of the pivoted links connected therewith, Figs. 2 and 3, for raising the floats to expose the landing wheels or for lowering the floats to cover the landing

wheels. In the latter operation, the landing wheel wells will be automatically closed beneath the wheels and in the first operation the wells will be opened to provide free passage to permit the wheels to project as the floats are lifted up over the same. Under both sets of conditions the landing gear is well capable of carrying the landing load and the shift from one form of landing gear to the other is quickly and positively accomplished.

In flight, the floats may be lowered to house the landing wheels, or be left lowered, if last in use, to preserve the stream lining of the ship. While desirable, it is not essential that the wheel wells be closed watertight as the buoyancy of the floats is preferably sufficient to carry the load even if the wells take in water. While the linkage shown operates satisfactorily to throw the bottom doors open and closed as the floats are lifted or lowered, cables or fluid pressure connections or the like may be employed for the purpose. Similarly, while the screw shaft and linkage construction disclosed is suitable for the raising and lowering of the floats, holding the same locked in either relation, other mechanisms for the purpose may be utilized and in fact many other changes in structure may be made all within the scope of protection afforded by the patent. The landing wheel posts being firmly connected with the fuselage and wing structure serve as practical guides for bracing and directing the floats in their up and down movements, the connected floats acting as a unitary frame sliding up and down over the posts. While the invention is shown in conjunction with a bi-plane, it will be obvious that it is equally well adapted for use with a monoplane or other forms of aerial apparatus.

The wheel wells may be made self-draining as by means of suitable vents or drains so that if they become filled to the water line when the plane is resting on the water, they will begin to drain as the plane "steps up" and will be practically dry by the time the plane leaves the water. Such a drain is indicated at 35, (Fig. 6), the same being equipped, if desired, with a one way valve preventing inflow when the plane settles on the water.

What is claimed is:

1. In combination with an airplane having landing wheels, floats for alighting said airplane on water and provided with housings to receive said landing wheels, means for raising and lowering said floats relative to said landing wheels to expose the landing wheels below the floats or to entirely house the wheels within the floats, said housings for the landing wheels including wells within the floats open at the bottom for the projection of the wheels and closures for said bottom openings automatically operable in

the raising and lowering of the floats to open and close said wheel wells.

2. Amphibian landing gear for air vessels, comprising land supports for alighting said vessel on land and supports for alighting said vessel on water, said latter supports having housings for the land supports and mounted for vertical movement on the vessel relative to the land supports to expose or cover said land supports at will, said water supports consisting of floats having wells for the land supports and means for automatically opening said wells for the protrusion of the land supports and for automatically closing the supports with the land supports housed therein.

3. In combination with an airplane of the "land" type equipped with landing wheels and posts carrying the same, floats, one for each wheel and each open at the bottom to pass up and down over the wheel, said floats being guided for vertical lifting and lowering movements over said wheel posts, each float having a well about the bottom opening for housing the wheel carried by the post and means for raising and lowering said floats at will to expose or to cover the wheels.

4. In combination with an airplane of the "land" type equipped with landing wheels and posts carrying the same, floats, one for each wheel and guided for vertical lifting and lowering movements over said wheel posts, each float having a well for housing the wheel carried by the post, means for raising and lowering said floats at will to expose or to cover the wheels, the wheel wells being open through the bottoms of the floats, doors for closing said bottom openings in the floats and means for automatically operating said doors in the lifting and lowering movement of the floats relative to the wheels.

5. In combination, an airplane having landing wheels and floats for sustaining the plane on land or water, said floats and landing wheels being movable relative to each other, the floats having wells to receive the landing wheels, said wells being open at the bottom to pass the wheels and equipped with automatic closures and means for automatically draining said wells when said automatic closures are closed and the plane "steps up" preparatory to leaving the water.

6. Amphibian landing gear for air vessels, comprising a land supporting means for alighting said vessel on land and a water supporting means for alighting said vessel on water, said water supporting means comprising a float having a well open through the bottom of the same for receiving the land supporting means, means for positively guiding said water supporting means up and down over and about the land supporting means, means for raising, lowering and holding said water supporting means relative to the land supporting means and means for closing and

opening the bottom of the well when the water supporting means is lowered to house the land supporting means or raised to expose the land supporting means.

5. 7. Amphibian landing gear for air vessels, comprising a land supporting means for alighting said vessel on land and a water supporting means for alighting said vessel on water, said water supporting means comprising a float having a well open through the bottom of the same for receiving the land supporting means, means for positively guiding said water supporting means up and down over and about the land supporting means, 10 means for raising, lowering and holding said water supporting means relative to the land supporting means, means for closing and opening the bottom of the well when the water supporting means is lowered to house 15 the land supporting means or raised to expose the land supporting means, said well closing and opening means including a closure for the open bottom of the well and actuating mechanism therefor automatically operable 20 by the raising and lowering movements of the 25 water supporting means.

8. In combination, an air vessel having a dependent landing device, a float for sustaining said air vessel on water, said float having 30 a vertically extending well to receive said landing device and open at the bottom to expose the landing device, means operable from the air vessel for raising and lowering said float over the landing device to thereby house 35 the landing device within said well or to leave said landing device projecting below the well, said raising and lowering means including mechanism for automatically securing the float in raised or lowered positions and closure 40 means for the bottom of the well operable to seal the landing device within the well when the float is lowered and to expose the landing device when the float is to be raised.

9. In combination, an airplane having a 45 landing device and a float, said float having a well receiving the landing device and open at the bottom to permit the landing device to project below the float, means for relatively shifting the float and landing device to effect 50 housing of the landing device within the well of the float or the exposure of the landing device below the float, a slide closure for the bottom opening of the float and means operable to slide the closure into closed position when 55 the landing device is housed within the well and to slide said closure to open position when the landing device is to be exposed below the float.

In testimony whereof I affix my signature.
JOHN C. WORTHINGTON.
